UNITED STATES PATENT OFFICE.

HENRY H. FEFELL, OF CINCINNATI, OHIO, ASSIGNOR OF ONE-HALF TO BENJAMIN T. STRING, OF NORWOOD, OHIO.

SEWING-MACHINE.

1,217,929.

Specification of Letters Patent.

Patented Mar. 6, 1917.

Application filed April 1, 1913. Serial No. 758,184.

To all whom it may concern:

Be it known that I, HENRY H. FEFELL, a citizen of the United States, residing at Cincinnati, in the county of Hamilton and State of Ohio, have invented certain new and useful Improvements in Sewing-Machines, of which the following is a specification.

My invention relates to two-thread sewing machines of the character of those in which the threads are caused to interloop in the absence of the passage of the supply end of either thread through the loop.

It is the object of my invention to provide means for imparting a novel movement to the looper; further, to provide novel means for adjusting the movement of the looper; further, to provide novel means for timing the movements of the looper with relation to the needle; further, to provide novel stitch-forming mechanism; further to provide novel means for controlling the passage of the needle thread; further to provide novel operating means for the looper; further to provide novel feeding means for the material; further, to provide novel adjusting means for said feeding means; and, further, to provide novel tensioning means for the needle-thread.

The invention will be further readily understood from the following description and claims, and from the drawings, in which latter:

Figure 1 is a front elevation of my improved device, part of the frame being broken away for better illustration of the parts.

Fig. 2 is a bottom view of the same.

Fig. 3 is a head end elevation of my improved device, with the needle-bar raised.

Fig. 4 is a head end elevation of my improved device, with parts of the frame omitted for better illustration of the working mechanism, and with the needle-bar in partly penetrated position.

Fig. 5 is a rear end elevation of my improved device, partly broken away.

Fig. 6 is an enlarged plan view of the looper mechanism showing the same with its looper in fully retracted position.

Fig. 7 is an end view of the same.

Fig. 8 is a similar view showing the looper in fully advanced position.

Fig. 9 is an end view of the same.

Fig. 10 is a diagrammatic plan view show-

ing the mechanism at one limit of adjustment for locating the position of the path of travel of the looper-eye, in full lines, and the opposite limit of said adjustment, in dotted lines, the normal widths of said paths being exaggerated.

Fig. 11 is a plan view exemplification of the paths of travel of the looper-eye at the respective exemplified limits of adjustment of length of the operating lever.

Fig. 12 is an axial section taken on the line 12—12 of Fig. 7, showing the eccentric adjusting connection for the supporting lever of the looper lever.

Fig. 13 is a cross-section of the same, on the line 13—13 of Fig. 6.

Figs. 14, 16, 18 and 20 are plan detail views showing various relations between the looper and the needle.

Figs. 15, 17, 19 and 21 are end elevations of the same, respectively.

Fig. 22 is a vertical section on the axial line of the needle, showing the needle penetrating the material and the formation of the needle loop.

Fig. 23 is a horizontal central section of the looper and needle, showing their eyes in coincident horizontal planes and showing the securing means of the looper on the looper lever.

Fig. 24 is a horizontal detail in section on the line 24—24 of Fig. 3, showing the tensioning means for the needle-thread between the take-up and needle; and,

Fig. 25 is a vertical longitudinal central section of the spool tension.

31 represents the frame of the machine in which a drive-shaft 32 is journaled in bearings 33, 34. This drive-shaft is shown as a crank-shaft having a crank 35 therein. It is arranged to have suitable driving mechanism secured thereto, as exemplified by the pulley 36.

A needle-bar 37 reciprocates in bearings 38, 39, in the overhanging head 40 of a bracket 41. (See Figs. 1 and 4.) A pitman 42 is articulated at 43 to the needle-bar and to a crank-pin 44 on a crank-disk 45 secured to the drive-shaft.

A presser-foot 47 (see Figs. 1, 3 and 4), reciprocates in a bearing 48 in the overhanging head and in a thimble 49 adjustable up and down in a threaded bearing 50 in said overhanging head. A wiper 53 is

secured to the bar 54 of the presser-foot and is arranged to be contacted by a lifter 55 for raising the presser-foot. A spring 56 is received about the presser-foot bar between the wiper 53 and the thimble 49, the tension of the spring being adjusted by said thimble.

The needle-thread is shown at 61, and in the present exemplification is arranged to be fed from a spool 62 secured to a taper-bushing 63, (see Figs. 1 and 25), the hole of the spool being slipped over the taper-bushing so as to be held tight frictionally by the bushing. The bushing has a flange 64. A spring 65 controls the tension of the needle-thread at the spool, being received over the flange 64 and adjusted by means of an adjusting screw 66, the spring being a leaf-spring rigidly secured to the frame by a clamp-screw 67, a coil-spring 68 being shown between the head of the adjusting screw and the leaf-spring. Washers 69, 70, preferably of cloth, are preferably respectively received between the flange 64 and the spring 65 and between the flange 64 and the base 71 from which a stem 72 extends, the bushing being received loosely about said stem.

The needle-thread passes through directing holes 75, 76, between which a take-up stand 77 is located, (see Figs. 1, 3 and 4), a take-up spring 78 being arranged to bear upon the needle-thread in certain parts of the movements of the mechanism. The upper end of the needle-bar is formed as a reciprocating take-up 79, being provided with a thread-contact part 80 received loopwise about the take-up stand.

The needle-thread is arranged further, in the present exemplification, (see Figs. 1 and 24), to pass through a needle-thread tension device 81 between the take-up device and the needle, instanced as leaf-springs 82, 82, located between fingers 83, 83, each provided with a thread guide-slot 85. The leaf-springs are secured to the front-cap 87 of the machine head by means of a clamp-bar 88 secured in place by a clamp-screw 89. An adjusting-screw 90 is adapted to bear against the springs for adjusting their tension and the normal frictional engagement thereof with the needle-thread. The cap is held to the head by the bolt 91.

The frictional resistance of these springs upon the thread is normally slight, but is arranged at certain parts of the movements of the mechanisms *i. e.* upon piercing movement of the looper-loop by the needle (see Figs. 17 and 19), to act to retard or hold the needle-thread, when the loop of the needle-thread has slipped off the looper, in order to aid in setting said loop of the needle-thread. This tension upon the needle-thread is accomplished by means of a plug 94 adapted to flex said springs for

increasing their frictional hold upon the thread.

The plug is shown reciprocating in a bearing 95 in the cap 87, its outer end being provided with an enlargement 96 for preventing loss of the plug and its inner end arranged to be contacted by a cam 97 adjustably located on the needle-bar by a set-screw 98 (see Figs. 1, 4 and 24).

The needle-thread is arranged to pass farther through a guide-hole 98 on the front cap and a guide-slot 99 on the needle-bar and through the eye 100 of the needle 101, secured in the needle-bar, as by means of a set-screw 102. (See Figs. 1, 3 and 22.)

The needle, in the present exemplification, is shown as having its eye projected in a line substantially parallel with the line of feed of the material, the said line of feed being indicated by the arrow *a*. (See Fig. 22). At its front, the needle has a long thread-receiving groove 104, extending upwardly from the needle-eye, and at its rear it has a short thread-receiving groove 105 extending upwardly from its needle-eye, and above the latter it further has a long thread-receiving groove 106, the grooves 105, 106, being separated by a hump 107. The grooves 105, 106, form substantially a long groove interrupted adjacent its lower end by the hump. The object of the hump is to throw the seam-limb of the needle-thread, which has penetrated the goods, rearwardly adjacent to the bight of the penetrated portion of the needle-thread, for forming a loop 108 upon the ascent of the needle, this loop, as hereinafter explained, being arranged to be received by the looper. The object of the long groove 106 is to permit piercing of the material by the needle without undue friction between the seam-limb of the needle-thread and the needle upon reciprocation of the needle. The object of the groove 104 is to prevent undue friction between the supply-limb of the needle-thread and the material in the reciprocating movement of the needle through the goods.

111 is a looper, which also acts as a loop-taker, looping about the needle and taking the loop of the needle-thread. This looper is arranged to be threaded with a looper-thread 112 through an eye 113 of the looper adjacent the loop-piercing end 114 thereof, (see Figs. 14 to 21 and Fig. 23). The eye is located in a finger 115 of the looper which also has a thread-groove 116 therein, the base of the finger having a thread-hole 117 therein, through which the looper-thread 112 is received (see Figs. 14 to 20), from a suitable source of supply, indicated as a spool 118, mounted and tensioned as described in connection with the needle-thread spool, the several parts thereof being indicated by similar but primed reference numerals.

115

120

125

130

130

The groove 116 is located in a substantially straight wall 119 of the finger, the eye 113 being in an enlargement 120 of said finger, the entering point 114 being at one side of said enlargement, and a reduced portion 121 of said finger being at the other side of said enlargement, the enlargement aiding in carrying back the needle-thread loop in the retracting movement of the finger out of the way of the descending needle.

The looper-thread is arranged (see Fig. 2) to be received through a hole 125 in the material supporting plate 126 of the frame 15 and a hole 127 in said plate extending lengthwise of said plate and opening adjacent to the looper for delivering said thread at said looper, and is acted on adjacent to a throat 128 of a throat-plate 129.

20 The looper-finger has a substantially elliptical path of movement, this path being indicated by the dotted line 131, (see Fig. 11), which indicates more particularly the path of the eye of the looper. Adjustment is provided for adjusting the minor axis of this substantially elliptical path so as to locate the sides of the path of the looper-finger closer to or farther from the longitudinal projection of the needle, a wider 25 path being indicated in Fig. 11 at 132, the object being to maintain the sides of this path as close to the needle as the conditions of operation will permit, especially at the advancing movement of the looper, this advancing movement being more nearly straight, as shown at 131^a and 132^a, than the retracting movement thereof, so that the point of the looper will be properly and effectively received in the loop of the 30 needle-thread.

I have also found it advisable to provide means for adjusting the position of the path of movement of the eye of the looper with relation to the longitudinal projection of the needle, that is, the axial line of the needle, so as to locate the major part of the path to the right and front or to the left and rear of the longitudinal projection of the needle, as indicated by the 35 light and heavy lines respectively in Fig. 10. The means whereby this is accomplished and whereby the movement of the looper is effected and adjusted and timed will now be described.

55 136 is a shaft journaled in bearings 137, 138, in the main frame, and has a crank-arm 139 thereon. (See Figs. 1, 2, 5, 6, 7, 8 and 9). 140 is a rocking pitman for driving the shaft 136 from the crank 35 of the 60 operating shaft. This pitman (see Figs. 1 and 5), which acts as a lever, has a bearing 141 about the crank and a variable speed connection with the shaft 136, exemplified as a slot and pin connection at the latter shaft and a varying pivot connection inter-

mediate of its ends. In the present exemplification the crank-arm 139 is provided with a slot 142 in which a drive-pin 143 is received and has sliding connection, for retarding the rotation of the shaft 136 during the movement of the crank-arm through the upper part of its rotation, (see Figs. 8 and 9), thereby providing a variable speed device for the looper. 144 is a stud on the main frame on which a block 145 is pivoted, 75 the pitman being provided with a slot 146 the walls of which have sliding connection with the block.

151 is a lever pivoted on a screw 152 secured to the main frame. (See Figs. 2, 80 3, 4, 6, 7, 8 and 9). A lever 153, instanced as an angle-lever in bell-crank form, is pivoted to the lever 151 by a stud-screw 154. Means are provided for driving each of these levers from the shaft 136, shown in 85 the form of eccentric connections, the eccentricities being so timed as to move the levers in dissimilar relations for effecting movements of the looper 111, which is located on the lever 153, as by having its shank 155 received in a hole 156 in the end of the lever 153, (see Fig. 23), the shank being clamped in place by a set-screw 157. This construction permits adjustment of the 90 looper about the axis of the shank and also 95 positions the looper in and out with relation to the pivot of the lever.

The eccentric connections mentioned are instanced as an eccentric 161 on the shaft 136 about which a strap 162 of a link 163 100 is received, the link having operative connection with the lever 151. (See Figs. 2, 6, 7, 8 and 9). I have instanced this link as a two-part link, so as to permit adjustment of its length, mainly however for the 105 purposes of assembling, instanced as the parts 164, 165, having threaded connection 166, 167, locked in place by a lock-nut 168.

The connection between this link and the lever 151 is preferably an adjustable connection, (see also Figs. 12 and 13), this adjustable connection being instanced as a connection for varying the length of the lever and for varying its positions of limits of movement. This is instanced as a crank-block 171 having a crank-pin 172 thereon. The crank-pin is received in a bore 173 in the lever 151, in which it is lengthwise positioned and clamped in place by a set-screw 174. The crank-block has a pin 175 thereon having a rounded head 176 received in a rounded recess in a bushing 177, clamped in a split-bearing 178 in the link 163 by means of a clamp-screw 179.

The means for operating the lever 153 is 125 similar to the means described for operating the lever 151 and is instanced as an eccentric 181 on the shaft 136 about which a strap 182 of a link 183 is received, the link being shown as a two-part link, com- 130

prising the parts 184, 185, having threaded connections 186, 187, between the same, and a lock-nut 188.

The power end of the bell-crank lever is 5 provided with a plug 189 having a rounded portion 190 about which a bushing similar to the bushing 177 is received, this bushing being clamped in a split-bearing 191 by means of a clamp-screw 192. This construction 10 permits rocking movement between the links and the power ends of said levers. Figs. 6 and 7, and Figs. 8 and 9, indicate the respective limits of movement of the parts.

The constructions just described impart 15 a substantially elliptical path of travel to the looper, and this path of travel further preferably has one of its sides flattened, or describes a path more nearly parallel to the major axis of the substantially elliptical path, 20 during the loop-taking stretch of movement of the loop-taker, whereby I am enabled to cause the looper to move in a path close to the needle during its loop-taking movement without at the same time causing friction 25 between the needle and the looper or causing interference between the looper and needle. It also imparts a closed path of movement to the looper, and permits a substantial retarding of the looper at a portion 30 of its path while the needle maintains its speed of its reciprocating motion, so that the needle will complete the upward portion of its travel and arrive at the looper at its proper time for piercing the loop formed by the looper-thread in the retracting 35 movement of the looper, in other words, the looper is retarded in its movement so as to wait upon the needle, so that upon the descent of the latter, the looper-eye will be 40 in the correct position for having the needle act upon the looper-thread.

Referring to the motion imparted by the pitman from the drive-shaft to the lower shaft, (see Fig. 5), the drive-shaft rotates 45 continuously at a given rate of speed. The slip-connection between the drive-shaft and the lower-shaft causes uniform movement of the lower shaft with the drive-shaft throughout those portions of the rotation of 50 the drive-shaft at which the crank-pin is radially equi-distant from the axis of rotation of the lower shaft. This substantial equi-distance is during that portion of the travel of the needle at which the needle is 55 in substantially its lowermost position and in the forepart of its ascending movement and while the looper is acting to take the loop of the needle-thread. (See Figs. 6 and 7). This imparts a quick motion to the 60 looper during its loop-taking function.

This loop-taking function takes place on the initial portion of the ascent of the needle, the next function of the looper being to arrange the looper-thread in position to be 65 pierced at the final portion of the next de-

scending movement of the needle. For accomplishing this it is necessary for the needle to pass through by far the greatest portion of its movement, while at the same time it is necessary for the looper to pass 70 through by far the smaller portion of its movement, the crank-pin 143 passing lengthwise of the slot 142. (See Figs. 8 and 9.) In order, therefore, to relatively time these movements, I provide the variable speed de- 75 vice, which I have described.

To illustrate the relative movements of the needle and looper, and referring to Figs. 14 to 21 inclusive, Figs. 14 and 15 represent respectively a top and an end view of the 80 needle and looper positions at which the needle is beginning its looper-loop piercing movement. In this position the needle-thread loop 108 is about the finger of the looper, the said loop passing through a previously formed set-loop of the looper-thread, and the thread-eye of the looper is advanced through said needle-thread loop to a position in advance of said needle-thread loop, carrying the looper-thread with 85 it through the needle-thread loop in the formation of the looper-loop 193.

Figs. 16 and 17 represent respectively a plan view and an end view of the next main step in the formation of the stitch, showing 90 the needle in looper-loop penetrating position, the looper being partially retracted, and the loop of the needle-thread about to slip off the finger of the looper. It is just subsequent to this position that the supply 95 portion of the needle-thread is acted on by the tension device 81 for holding the same and causing the needle in its further descent to draw upon the needle-loop just formed for beginning the setting of the 100 same. The needle-loop just formed is further set upon the ascent of the needle-bar, when the take-up mechanism acts on said 105 needle-loop for setting the stitch.

Figs. 18 and 19 represent respectively a 110 plan view and an end view at the next main position of the needle and looper, which is at a point immediately subsequent to the point of farthest descent of the needle and farthest limit of retraction of the looper. 115 It will be noticed that the looper has now looped its thread about the needle, preparatory to its next advancing movement, to take the loop formed in the seam-end of the 120 needle-loop.

Figs. 20 and 21 represent respectively a plan view and an end view of the next main step in the relation of the needle and looper, instanced as the loop-penetrating movement of the looper. The needle at this point has 125 begun its ascent, whereby the seam-limb of the loop of the needle-thread has been thrown out by the hump 107 in the rear groove of the needle, for permitting the same to be taken by the looper. 130

The looper will now have passed through the greater portion of its path of movement, while the needle will have passed through only a small portion of its range of movement. It is at this point that the variable speed device hereinbefore described (see Figs. 3, 8 and 9) becomes effective, for retarding the movement of the looper for varying its speed and allowing it to wait 10 upon the needle, which must meanwhile pass up and down throughout the greater portion of its range of movement, so that when the needle again arrives at the position shown in Figs. 14 and 15, the looper will have 15 passed through only a short portion of its path to be in position to have its loop pierced by the needle.

It will be noted that throughout these variations that there is throughout a comparatively small movement of the looper about the longitudinal projection of the axis, or axial line, of the needle, thereby avoiding the necessity of take-up mechanism for the looper-thread.

196 is a feeding-foot reciprocating and movable up and down in the material support and is suitably secured to a feeding-foot lever 197, which has a slot 198 therein, in which an eccentric pin 199 on the lower 25 shaft operates. The upper and lower walls of the slot are contacted by the eccentric pin for raising and lowering the feeding-foot, and the slot is of such length as to permit the eccentric-pin to move lengthwise 30 thereof for imparting the least feeding movement desired. (See Figs. 1, 2, 3 and 4.) The forward end of the lever has an end-slot 200 in which a pivot-screw 201 is received, the pivot-screw being secured to the 35 frame. 202 is a spring received about screws 203, 204, respectively on the frame and on the feeding-foot lever, for normally drawing the lever forward and causing a cushion-block 205 to contact the eccentric-pin.

40 The forward movement of the feeding-foot lever is limited by the cushion-contact part 206 on a lengthwise slidable bar 207 slidable in a bearing 208 through which a limiting-screw 209 is received through a 45 diagonal slot 210 in the lengthwise slidable bar. A positioning-block 211 is received through a slot 212 in the frame, lengthwise of which it may be clamped by a clamp-screw 213, the positioning-block having articulation with the lengthwise slidable bar, as shown by the pivot-screw 214.

Having thus fully described my invention, what I claim as new and desire to secure by Letters Patent, is:

60 1. In a sewing machine employing a reciprocating needle, the combination of a looper, a lever on which said looper is located, a lever on which said last-named lever is pivoted, eccentric means for rocking

said levers, the power end of said last-named lever being adjustable in length. 65

2. In a sewing machine employing a reciprocating needle, the combination of a looper, a lever on which said looper is located, a lever on which said last-named lever is pivoted, means for rocking said levers, and means whereby the power end of said second-named lever is adjustable in length for adjusting the position of the path of movement of said looper. 70 75

3. In a sewing machine employing a reciprocating needle, a looper coacting with the needle of said machine, an angle-lever on which said looper is located, a second lever on which said last-named lever is pivoted, a crank-arm for operating said levers, and a slot-and-pin drive-connection for operating said crank-arm and thereby qualifying the speed of movement of said looper relative to the speed of movement of the needle. 80 85

4. In a two-thread sewing machine of the character described employing a reciprocating needle having a thread-eye adjacent its goods-penetrating end, of a loop-taking looper having a thread-eye adjacent its loop-piercing end, an angle-lever on which said looper is located, a second lever on which said angle-lever is pivoted, eccentric mechanisms for moving said levers for causing said thread-eye of said looper to describe a closed path of movement about the longitudinal projection of the needle which is substantially elliptical in form, the sides of said path of movement being closely adjacent to said longitudinal projection, and means for driving said eccentric mechanisms comprising a variable-motion device for qualifying the speed of movement of said looper adjacent to one end of the path thereof with relation to its speed adjacent to the other end of its path. 90 95 100 105

5. In a two-thread sewing machine of the character described employing a reciprocating needle having a thread-eye adjacent to its piercing end, of a loop-taking looper having a thread-eye adjacent its loop-piercing end, a lever on which said looper is located, a second lever on which said looper-lever is pivoted, means for reciprocating said levers for causing movement of said thread-eye of said looper in a closed path which is substantially elliptical, one side of which is more nearly parallel to the major axis of said substantially elliptical path than the other side thereof, said side so more parallel being the needle-thread loop-piercing movement of said looper, and means for retarding the movement of said looper adjacent one of the limits of reciprocating movement of said needle with relation to its speed adjacent to the other end of its path. 110 115 120 125

6. In a sewing machine of the character

described employing a reciprocating needle, a looper provided with a thread-eye having a substantially elliptical closed path of movement about the axis of the needle position, and means for imparting relatively different speeds to the thread-eye adjacent to the respective ends of the path of movement of said thread-eye including eccentrics, a lever actuating said eccentrics and a pivot on which said lever has lengthwise movement for causing variations in speed of rotation of said eccentrics during portions of their rotations.

7. In a sewing machine of the character described employing a reciprocating needle, a looper coacting with said needle, a lever on which said looper is pivoted, a lever on which said first-named lever is pivoted, eccentrics for operating said levers, and means for rotating said eccentrics comprising a lever and a pivot on which said last-named lever has longitudinal movement for causing variations in speed of rotation of said eccentrics during portions of their rotations for causing a dwell in the movement of said looper in a portion of said substantially elliptical path.

8. In a sewing machine of the character described employing a reciprocating needle, a looper coacting with said needle, a lever on which said looper is pivoted, a lever on which said first-named lever is pivoted, eccentrics for operating said levers, means for rotating said eccentrics comprising a lever and a pivot on which said last-named lever

has longitudinal movement for causing variations in speed of rotation of said eccentrics during portions of their rotations for causing a dwell in the movement of said looper in a portion of said substantially elliptical path, and means for adjusting the length of said second-named lever.

9. In a sewing machine of the character described employing a reciprocating needle, a looper coacting with said needle, a lever on which said looper is pivoted, a lever on which said first-named lever is pivoted, eccentrics and links for operating said levers, means for adjusting the articulation of said second-named lever with its link for adjusting the effective length of said link, means for rotating said eccentrics comprising a lever, a pivot therefor on which said last-named lever has longitudinal movement, a crank-arm actuating said eccentrics, and a slot-and-pin drive-connection between said last-named lever and crank-arm, for causing variations in speed of rotation of said eccentrics during portions of their rotations for causing a dwell in the movement of said looper in a portion of said substantially elliptical path, and means for adjusting the length of said second-named lever.

In testimony whereof, I have hereunto signed my name in the presence of two subscribing witnesses.

HENRY H. FEFELL.
